UNITED STATES PATENT OFFICE.

JAMES MAXEY BROOKS, OF MOLENA, GEORGIA.

WHEELED SCRAPER.

SPECIFICATION forming part of Letters Patent No. 744,856, dated November 24, 1903.

Application filed May 6, 1903. Serial No. 155,875. (No model.)

To all whom it may concern:

Be it known that I, JAMES MAXEY BROOKS, a citizen of the United States of America, and a resident of Molena, county of Pike, State of Georgia, have invented certain new and useful Improvements in Wheel-Scrapers, of which the following is a full, clear, and exact description, reference being had therein to the accompanying drawings, in which—

10 Figure 1 is a perspective view of the machine loaded; Fig. 2, a plan view of the same; Fig. 3, a side view of the same, the near wheel being removed; Fig. 4, a view in detail showing the position of some of the parts while in the act of dumping; Fig. 5, a detail perspective of the end gate; Fig. 6, a view of the machine in the act of loading, the near wheel being removed; Figs. 7, 8, 9, and 10, detail views hereinafter described; Fig. 11, a side 15 elevation showing the manner of connecting a pair of scrapers when used in tandem; Fig. 12, a detail perspective of the frame used in connecting the scrapers when used in tandem; and Fig. 13, a side elevation showing 20 the apparatus converted into a log-cart, the near wheel being removed.

25 The object of this invention is principally to improve the load elevating and dumping devices and also to render the machine readily convertible into a tandem excavator, a log-cart, a two-wheeled dump-cart, and a wagon, thereby especially adapting the machine for general contracting-work.

The invention also has other objects in view, which will appear in the course of this specification.

Referring to the drawings by reference-letters, the draft appliance consists of a tongue *a*, attached at its rear end to a cross-bar *b*, 30 which is braced to the tongue by the draft-bars *c*, which are long enough to extend back to the rear of the arch of the axle *d* and are each provided with an upward-extending arm *e* at its rear extremity, these arms extending 35 up above the spindles of the axle and being pivotally connected by removable horizontal bolts *f* to the rear ends of side bars *g*, which are parts of a frame or yoke consisting of said side bars and a front cross-bar *h*.

40 The side bars *g* are rigidly attached to the vertical parts of the arch of the axle and are

braced by the forwardly-inclined braces *i*, rigidly connecting the bars *g* to the axle-spindles, whereby said frame and the axle move as a single frame.

55

Journalized in suitable brackets *j*, attached to the side bars *g* near the front bar *h*, is a rock-shaft *k*, extending entirely across the front of the machine parallel to the front bar *h*, and rigidly attached to this rock-shaft 60 is a stop *l*, which engages under the bar *h* and limits the movement of said shaft. The ends of said shaft beyond the side bars *g* are formed into cranks *m*, which carry brake-shoes *n*, which are adapted to bear upon the 65 tires of the wheels. One end of said shaft carries an operating-handle *o*, which lies outside of one of the transporting-wheels and extends toward and a little below the hub thereof to be within convenient reach of the 70 driver, who usually walks along by the side of the machine.

Pivoted to the front bar *h* is a latch *p*, which is adapted to normally engage under the projecting edge of a plate *q*, bolted on 75 the rear end of the tongue, and whose handle *r* extends toward one side of the machine far enough to be reached by the driver without passing in front of the machine.

The scraper-pan *s* is pivotally hung about 80 midway its length by vertical hangers *t*, bolted to the side of the scraper and extending up above the top edges of the same, removable bolts *u* being employed to pivotally connect the upper ends of these hangers to the 85 upturned ends *e* of the draft-irons.

The draft-hooks *v* engage draft-eyes *w*, attached to the sides of the pan, these hooks inclining upward and forward and being pivotally connected by bolts *x* to the draft-bars 90 *c*, each hook being provided with an arm *y* at its upper end which curves upward and rearward and normally rests upon the rear part of bar *o'* and the forward end of a trip-lever *z*, which is pivotally supported on a 95 shoulder-bolt *z'* between one of the hangers *t* and the adjacent side of the scraper and whose rear end is pivotally connected at *a'* to a bar *b'*, pivotally supported at *c'* on the side of the scraper and extending rearward beyond 100 the scraper. The bar or lever *z* is slotted at *d'* where its pivot passes through in order

that it may have a limited longitudinal play when it is vibrated on its pivot, and thereby avoid binding.

To the rear end of each of the levers b' is pivotally connected a link e' , which extends upward and forward and is pivotally connected to a standard f' , loosely attached to the axle-spindle. Each of these standards f' is provided with a bearing in its upper end, and in these bearings is journaled a transverse rock-shaft g' , whose ends beyond said standards are each cranked and provided with a brake-shoe h' to engage the surface of the wheel-tire. One end of this shaft g' is provided with an operating handle or lever i' , which lies outside of one of the wheels and extends toward the hub thereof. The handles o and i' are preferably at the left side of the machine.

20 To limit the depth of the cut, I employ suitable limiting devices j' , connecting the brace i or any other part of the frame carried by the axle in front of the same to the draft appliance. In the present instance I employ a 25 chain and a plate k' , pivotally connected to the draft-iron by the bolt x , which supports the pivotal draft-hook v , this plate k' being provided with a series of holes for adjustment purposes; but it will be observed that I may 30 employ any suitable adjustable devices in lieu of this chain and perforated plate.

In front of each hook v is mounted a downward-inclined bar l' , which terminates in front of said hook and the eye w and in line therewith, and which has its upper end rigidly connected to the draft-irons by one or more rivets m' . The front edge of each of these bars l' may be sharpened somewhat, so that they will act as a cutter to cut roots and 40 clods. These bars will also act as fenders to prevent clods and stones interfering with the proper action of the hooks and eyes or loops. Each of these fenders or colters is braced by an upward and rearwardly inclined brace n' , 45 connecting it to the draft-iron. This brace n' is formed, preferably, by a downward continuation of the rear end of a bar o' , bolted to the side of the main draft-irons by rivets m' and x . The forward ends of bars l' are 50 carried around the front corners of the draft-irons and bolted to the tongue, as shown more clearly in Fig. 2, thereby strengthening the weakest points in the draft-irons—namely, the front corners thereof.

55 When the machine is in the act of loading, the parts are positioned as shown in Fig. 6—that is, the draft-hooks v are in engagement with the loops w and their trip-arms y are off the trip-levers z , the levers y and b' , which 60 form a sort of toggle-lever, are in alinement, and the brake-shoes and their shafts are in the position shown.

When the scraper is loaded and it is desired to elevate the same, the driver grasps 65 lever o and presses it backward toward the hub until the brake-blocks bear firmly against the wheel-tires, whereupon the forward mo-

tion of the wheels will carry the arch of the axle upward and the upper end of the frame $g\ h$ downward and forward until the latch p 70 engages plate q and latches the forward end of the frame down, whereupon the driver will release the handle o . When the forward end of the frame is thus carried down, its rear end is elevated and carries with it the 75 uprights e , on which is hung the scraper, thereby elevating the scraper to the position shown in Fig. 3, latch p holding it in that position while it is being transported to the dump-place. When the pan is thus elevated, 80 the scraper swings forward and brings the hooks v to the rear ends of the loops or eyes, as shown in Fig. 3.

In dumping, the driver simply takes hold of lever i' and pulls it rearward to apply 85 the brake-blocks h' to the wheels, which action carries the standards f' forward and through the medium of the links e' and toggles b' and z lifts the draft-hooks out of the draft-eyes. The continued movement forward of the standards f' then lifts the rear 90 end of the scraper-pan and dumps the pan in the usual way by inverting it. After the pan is dumped it may be readily swung back into the position shown in Fig. 3 and be then transported back to the loading-place.

When it is desired to drop the pan to load, the driver simply reaches in and releases latch p , whereupon the scraper drops to loading position. If desired, an end gate r' may be employed to close the front end of this pan when 100 it is elevated. This end gate may be conveniently pivoted upon the side bars g by means of bolts s' , the gate being provided with suitable side arms t' for this purpose and suitable forward-projecting lugs u' , adapted to engage over the front edge of the cross-bar h' to prevent the end gate dropping downward too far. Located and supported in this manner, the 105 end gate automatically drops down in front 110 of the scraper when the same is elevated by the downward movement of the frame $g\ h$, as shown in Fig. 3. When the said frame $g\ h$ is elevated and the scraper-pan drops, this end gate is lifted out of the way, as shown in Fig. 6. 115

This machine possesses a number of very important advantages. An important feature lies in utilizing the forward motion of the apparatus to both elevate the loaded pan and to dump it and to arrange the operating-handles at the side of the machine where they will be within convenient reach of the driver, who usually walks along by the side of the machine. It will be noted that these handles are arranged substantially radial, so that they 120 are always within easy reach of the driver no matter what position the brake-shoes may be in. It will be noted, further, that by pivotally hanging the scraper at a point well up and by employing the peculiar arrangement of 125 devices shown and described for unlatching the draft-hooks all danger of the pan being prematurely dumped while being transported to the dump-place is avoided, for even though

- the front edge of the pan should engage an obstruction which would tend to dump it the draft-hooks would engage the forward ends of the draft-eyes and prevent the pan from being dumped, the draft-hook eyes being prevented from missing the draft-hooks by reason of the position of the draft-hooks and the elevated point of pivotal support on the pan, as is evident from a glance at Fig. 3.
- 10 To convert the apparatus into a log cart or truck, as shown in Fig. 13, it is simply necessary to remove the pan by detaching its bolts *u* and the links *e'*. Then by hitching suitable chains *x'* to the arch of the axle, the same being lowered, and passing said chain under the log to be transported, the front end of the log may be elevated by the elevating-brakes and latched in that position and be dragged away.
- 15 To arrange a pair of scrapers in tandem, as shown in Fig. 11, it is simply necessary to use a supplemental frame *y'*, (shown in detail in Fig. 12,) the forward ends of whose side bars are bent up and bolted to the standards *e*, carried by the front machine. This frame extends rearward beyond the ends of the bars *b'* and links *e'* and is provided with a suitable strap or loop *z'*, into which the forward end of the tongue of the rear machine may be bolted, this tongue being shortened in order that the two machines shall be brought close together and be substantially one machine. The frame *y'* is wide enough to avoid interference with the free operation of the parts of the front machine, so that each machine will be free to operate as when used singly. These tandem machines are of great value where the length of the haul is so great as to make it advisable to increase the capacity of each machine.
- 20 or enable each team to double its capacity. Of course these tandem machines can only be employed in earth that is comparatively easy to excavate. It will be observed that the forward upward-turned ends of the side bars *y'* are bolted to the uprights *e* by the same bolts *f* and *u* that attach these uprights to the hangers *t* and the side bars *g*.
- 25 As shown in Figs. 2 and 3, a seat *b* for the driver may be mounted on the rock-shaft *g'*, which the driver may use while the load is being transported to the dump.
- 30 As will be observed, the seat normally inclines slightly downwardly and forwardly, whereby when the driver is in place thereon his weight will tilt the seat up to an approximately horizontal position, and thereby hold the brake-shoes *h'* off the wheels.
- 35 In addition to limiting the depth of the cut, the chains *j'* serve another purpose—namely, to lift upward on the draft appliance, and thereby counteract the downward pull on the draft-hooks, whereby the draft appliance will be greatly strengthened.
- 40 Having thus fully described my invention, what I claim, and desire to secure by Letters Patent, is—
1. In a wheel-scraper, the combination of

an arched axle supported on wheels, a draft appliance, a scraper-pan supported thereon, a load-elevating device adapted to engage the wheels, and an end gate carried thereby.

2. In combination, an axle and wheels, a frame mounted thereon, a draft appliance connected to the frame at the rear of the axle, a scraper or pan supported on the draft appliance to the rear of the axle, a wheel-engaging brake device supported on the forward end of said frame, and an end gate pivotally supported in the forward end of said frame, for the purpose set forth.

3. In combination with an axle and a pair of wheels, a frame supported on the axle, a draft appliance connected to the frame to the rear of the axle, a scraper-pan supported at the rear of the axle, and a wheel-engaging device supported on the forward end of said frame, whereby the loaded pan may be elevated by the forward rotation of the wheels.

4. In combination, an axle and wheels, a frame supported on the axle, a rock-shaft journaled in its forward end and provided with cranks and brake-shoes and an operating-handle, a draft appliance pivotally connected to said frame to the rear of the axle, and a scraper-pan pivotally supported on the draft appliance.

5. In combination with an axle and a pair of wheels and a draft appliance, a scraper-pan pivotally supported on the draft appliance in the rear of the axle, a frame carried by the axle and attached to said draft appliance, a wheel-engaging device carried by said frame and provided with an operating-handle lying outside of the wheels.

6. In combination, an axle and wheels, a frame on the axle, a draft appliance connected to said frame at the rear of the axle, a scraper-pan pivotally hung on said draft appliance, a rock-shaft on the forward end of the frame provided with cranks and brake-shoes adapted to engage the wheels, and an operating-handle connected to said rock-shaft at one end and extending toward the hub of the wheel on the outside thereof, for the purposes set forth.

7. In combination, an axle and wheels, a frame supported thereon and carrying wheel-engaging devices, a draft appliance provided with side bars extending rearward under the axle and having upward extensions at their rear ends, said upward extensions being pivotally connected to said frame, and a pan pivotally hung from said upward extensions.

8. In combination, an axle and wheels, a frame carried by the axle, a draft appliance connected thereto, a pan, draft-hooks connected to the draft appliance and devices on the pan for engagement with these hooks, and fender-bars extending downward and rearward in front of said draft-hooks.

9. In combination, an axle and wheels, a draft appliance and a pan pivotally hung therefrom, draft-hooks and draft-eyes, and

- 1 fender-bars attached to the draft appliance and extending downward and rearward in front of said draft hooks and eyes, and braces for these fender-bars.
- 5 10. In combination, an axle and wheels, a draft appliance, a pan, pivoted draft-hooks carried by the draft appliance, each draft-hook being provided with a rearward-extending arm, and means for automatically tripping these arms to unlatch the draft-hooks during the dumping operation.
11. In combination, an axle and wheels, a draft appliance and a scraper-pan pivotally hung from the draft appliance to the rear of the axle, a frame on the axle, and an adjustable depth-regulating device connecting the frame on the axle with the draft appliance at a point in front of the axle, for the purpose set forth.
- 15 12. In combination, an axle and wheels, a draft appliance, a scraper-pan pivotally hung, standards supported pivotally on the axle, a rock-shaft journaled in these standards and provided at its ends with cranks and brake-shoes, a handle attached to this rock-shaft and extending inward toward the hub at one side of the machine, and means connecting said standards to the rear end of the pan, whereby the forward motion of the wheels
- 20 25 30 may be utilized to dump the pan.
13. The combination of an axle and wheels, a draft appliance and a pivotally-hung scraper-pan, standards supported on the axle and carrying wheel-engaging devices at their outer ends, means connecting said standards to the rear end of the pan, whereby the forward motion of the wheels may be utilized to dump the pan.
- 35 40 45 14. In combination, an axle and wheels, a draft appliance and a pivotally-hung scraper-pan, radial standards, wheel-engaging devices carried thereby, draft-hooks carried by the draft appliance, and devices connecting said standards to the rear end of the pan and adapted to automatically unlatch said draft-hooks when the pan is dumped.
15. In a wheel-scaper, the combination of an axle supported on wheels, a draft appliance and a scraper-pan, wheel-engaging load-elevating devices, wheel-engaging dumping devices, and operating-handles for these devices, these handles being located outside of one of the wheels, for the purpose set forth.
- 55 60 65 16. In combination, an axle and wheels, a draft appliance and a scraper-pan hung to the rear of the axle, a frame on the axle, and a depth-regulating device connecting the frame and the axle with the draft appliance in front of the axle.
17. The combination of an axle and wheels, a draft appliance and a pivotally-hung scraper-pan, standards supported on the axle, a rock-shaft carrying brake-shoes and a lever for operating it, means connecting the standards to the rear of the pan, whereby the forward motion of the wheels may be utilized to dump
- the pan, and a driver's seat mounted on said rock-shaft.
18. In a wheeled scraper, the combination of an axle and wheels, a draft appliance, a scraper-pan, wheel-engaging dumping devices, and a driver's seat mounted thereon.
19. In a wheeled scraper, the combination of an arched axle supported on wheels, a draft appliance, a scraper-pan, a load-elevating device adapted to engage the wheels, and an end gate carried thereby.
20. In a wheeled scraper, the combination of an arched axle supported on wheels, a draft appliance, a scraper-pan, a load-elevating device adapted to engage the wheels, and an end gate pivotally depending therefrom.
21. In combination with an axle and a pair of wheels, a draft appliance, a scraper-pan pivotally supported in the rear of the axle, a frame carried by the axle and attached to said draft appliance, a wheel-engaging device carried by said frame and provided with a handle lying outside of the wheels.
22. In combination with an axle and a pair of wheels, a draft appliance, a scraper-pan pivotally supported in the rear of the axle, a frame carried by the axle and attached to said draft appliance, a wheel-engaging device carried by said frame and embodying a rock-shaft provided at each end with a handle lying outside of the adjacent wheel.
23. In combination, an axle and wheels, a draft appliance, a scraper-pan pivotally hung, standards supported pivotally on the axle, and a load-dumping means supported on said standards and provided with an operating-handle lying outside of the wheels and extending toward the axle.
24. In a wheeled scraper, the combination of an axle supported on wheels, a draft appliance and a scraper-pan, wheel-engaging load-elevating devices, and wheel-engaging dumping devices independent of the load-elevating devices, substantially as set forth.
25. In a tandem wheeled scraper, the combination of a front machine and a rearward-extending frame y' attached to the draft appliance of the front machine, and a rear machine having its draft appliance connected to the rear end of said frame y' , for the purposes set forth.
26. In a machine of the class described, the combination of an arched axle supported on wheels, a frame supported on the axle, a draft appliance connected to said frame in rear of the axle, wheel-engaging devices carried by the forward end of said frame, and load-sustaining devices, for the purposes set forth.
- In testimony whereof I hereunto affix my signature, in the presence of two witnesses, this 17th day of April, 1903.
- JAMES MAXEY BROOKS
